(57) **CLAIM**

(51) LOC (7) Cl. **13-01**

The ornamental design for a stator of AC generator for vehicles, as shown.

(52) U.S. Cl. **D13/122**

DESCRIPTION

(58) **Field of Search** D13/118, 122;

FIG. 1 is a front, and top side perspective view of a stator of AC generator for vehicles showing our new design;

310/52, 179, 180, 201, 254-260

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof; and,

FIG. 7 is a left side elevational view thereof.
